UNITED STATES PATENT OFFICE.

CHARLES F. ROPER, OF HOPEDALE, MASSACHUSETTS, ASSIGNOR TO
DRAPER COMPANY, OF HOPEDALE, MASSACHUSETTS, A CORPORA-
TION OF MAINE.

HARNESS-MOTION FOR LOOMS.

No. 802,659.

Specification of Letters Patent.

Patented Oct. 24, 1905.

Application filed March 15, 1905. Serial No. 250,136.

To all whom it may concern:

Be it known that I, CHARLES F. ROPER, a citizen of the United States, residing at Hopedale, county of Worcester, State of Massachusetts, have invented an Improvement in Harness-Motions for Looms, of which the following description, in connection with the accompanying drawings, is a specification, like numerals on the drawings representing like parts.

This invention relates to harness-motions for looms; and it has for its object the production of simple, efficient, and positively-acting means to effect the reciprocation in both directions of the harness or heddle frames without the use of straps, bands, or other similar flexible connections. The actuation of the harness-frames is effected by means located principally above the frames and external to the loom side, leaving an unobstructed space beneath the harness-frames.

My invention is particularly applicable to "plain" or two-harness looms and gives a smooth positive motion to the harness-frames with very simple and durable mechanism.

The various novel features of my invention will be fully described in the subjoined specification and particularly pointed out in the following claims.

Figure 1 is a front elevation, centrally broken out, of a harness-motion embodying my present invention, a sufficient portion of the loom to be understood being illustrated in connection therewith. Fig. 2 is a right-hand side elevation of the actuator and the coöperating portions of the transmitting means intermediate the actuator and the harness-frames. Fig. 3 is a detail in front elevation, showing the actuator and coöperating transmitters in the extreme opposite position from that shown in Fig. 1; and Fig. 4 is a perspective view of the actuator detached.

In Fig. 1 I have shown each of the two harness-frames as consisting of a cross-bar 1 and two suitably-attached side bars 2, the former being adapted to support a series of heddles 3 of well-known construction, the side bars being vertically slidable in vertical guides 4, secured to or forming a part of brackets 5, mounted on the loom-frame. The guides 4 maintain the harness-frames in their proper vertical paths as they are reciprocated oppositely by means to be described.

In Figs. 1 and 2 the front harness-frame is depressed and the rear frame elevated. 55

The upper ends of the side bars 2 of each harness-frame are connected by links 6 and 7 with the transmitting means to be described, and, as shown in Fig. 1, the opposed faces of the links and side bars are transversely corrugated at 8 and held together by bolts 9, passed through slots 10 in the links. By means of the slots the links can be adjusted and the corrugated faces hold the adjacent parts firmly together when the bolts are set up. The links 65 connect each harness-frame with a pair of bent levers or bell-cranks 11 12, the levers 11 being herein shown mounted side by side to rock on a fixed fulcrum 13 on the arch 14 of the loom, while the levers 12, which I have hereinafter 70 termed "transmitters," are mounted side by side to rock on a fixed fulcrum 15 on the arch. Each pair of levers 11 12 is connected by a link 16 (see Fig. 1) to rock in unison in the same direction to thereby raise or lower the connected 75 harness-frame.

The levers or transmitters 12 are each provided with a two-part cam-follower, herein shown as two arms 17 18, extending on opposite sides of its fulcrum, and provided with 80 rolls 17^x 18^x, respectively.

The pairs of levers mounted and connected as described and the construction of each lever or transmitter 12 may be and are all substantially as shown and described in United 85 States Patent No. 770,116, granted to me September 13, 1904, to which reference may be had.

I have provided a common oscillating actuator to coöperate positively with the two transmitters and effect rocking movement thereof 90 in opposite directions to thereby cause the vertical and opposite reciprocation of the two harness-frames. The actuator is made as a casting having a hub 19, two cams 20 21, extended oppositely from each other, and a third cam 95 22, projecting from the hub substantially at right angles to the other two cams and laterally offset therefrom, as shown in Figs. 2 and 4. The actuator is mounted to oscillate on a fulcrum-stud 23, fixed on a bracket 24, secured 100 to the side of the arch 14, (see Fig. 1,) the stud being parallel to the fulcras 13 and 15, the cams on the actuator being so located that the cam 22 is interposed between and coöperates with the two follower-rolls 17^x 18^x of 105 the front transmitter, while the cams 20 and

21 coöperate, respectively, with the similar rolls on the rear transmitter.

When the actuator is in the position shown in Fig. 1, the high part of cam 22 acts upon the front transmitter-roll 18^x to elevate it, and thereby position the transmitter to depress the front harness-frame, the corresponding roll 17^x then coöperating with the low part of cam 22. At the same time the high point of cam 20 is then acting on roll 17^x of the rear transmitter to elevate said roll and position the transmitter to raise the rear harness-frame, as will be manifest, the roll 18^x of the rear transmitter then coöperating with the low part 20^x between the cams 20 and 21. When the parts are in this position, it will be seen that the two harness-frames are practically locked in their extreme positions.

Referring now to Fig. 3, the actuator is shown in the opposite position, and at such time the high part of cam 22 has acted through the front transmitter-roll 17^x to rock its transmitter into the position shown to elevate the front harness-frame. At the same time the cam 21 has acted to elevate the roll 18^x of the rear transmitter, rocking the latter into position to depress the rear harness-frame, while the corresponding roll 17^x is on the low part 20^x. The front transmitter-roll 18^x is then on the low part of the cam 22, and the front and rear harness-frames are held locked in raised and depressed positions, respectively.

It will be understood that the oscillation of the actuator from one to the other of its extreme positions operates through the two sets of cams to rock the two transmitters positively and in opposite directions.

The actuator may be oscillated by any suitable means, and herein I have employed substantially the means shown in United States Patent No. 737,149, granted to me on August 25, 1903. To this end the shaft 25, extended through the loom side, has fast upon it a crank 26, Fig. 1, provided with a radially-adjustable wrist-pin 27, on which is loosely mounted a sleeve 28, to which is pivotally connected at 29 the lower end of a link 30. A species of universal joint is thus provided between the link and the crank-pin, and the upper end of the link is pivoted at 31 to a coupling-link 32, pivoted at 33 on an extension 21^x of the cam 21 of the actuator. The link 30 is thus connected with the latter in such a manner as to oscillate the same by or through rotation of the shaft 25.

By adjusting the wrist-pin 27 on the crank the throw of the link 30 will be regulated as desired.

Inasmuch as the rear harness-frame has to rise a little higher and descend a little lower than the front harness-frame, the cams 20 21 are shaped to give such increased movement to the transmitter coöperating therewith and operatively connected with the rear harness-frame.

My invention is not restricted to the precise details of construction and arrangement herein shown and described nor to any particular form of means for effecting the oscillating movement of the actuator, as various changes or modifications may be made by those skilled in the art without departing from the spirit and scope of my invention.

Having described my invention, what I claim as new, and desire to secure by Letters Patent, is—

1. In a loom, in combination, two oppositely-movable harness-frames, a pair of connected levers operatively connected with each frame, an oscillating actuator positively coöperating with one of the levers of each pair, and means to oscillate the actuator and thereby effect reciprocation of the harness-frames. 80

2. In a loom, in combination, two oppositely-movable harness-frames, a rocking transmitter operatively connected with each frame, an oscillating actuator positively coöperating with the two transmitters, and means to oscillate the actuator and thereby effect reciprocation of the harness-frames. 85

3. In a loom, in combination, two oppositely-movable harness-frames, two rocking transmitters mounted side by side, suitable connections between each transmitter and one of the harness-frames, an oscillating actuator positively coöperating with and common to both transmitters, and means to oscillate the actuator and thereby effect the reciprocation of the harness-frames. 90

4. In a harness-motion for looms, two oppositely-movable and independent harness-frames, two rocking transmitters, a positive connection between each transmitter and one of the harness-frames, to reciprocate the latter, an oscillating actuator common to and coöperating with the transmitters, and means to oscillate said actuator. 100

5. In a harness-motion for looms, in combination, two harness-frames, fixed guides for each, two rocking transmitters, a fixed fulcrum therefor and on which they are mounted side by side, a positive connection between each transmitter and one of the harness-frames, an oscillating actuator common to and coöperating with said transmitters, to rock the same oppositely, and means to oscillate said actuator. 110

6. In a harness-motion for looms, in combination, two oppositely-movable harness-frames, a rocking transmitter positively connected with each harness-frame, an actuator having cams to coöperate with the two transmitters, to rock the same positively and oppositely, and means to oscillate said actuator. 120

7. In a harness-motion for looms, in combination, two oppositely-movable harness-frames, a rocking transmitter positively connected with each harness-frame, each transmitter having a two-part follower, a common actuator for the transmitters, having 130

cams to coöperate respectively with the followers of the transmitters, and means to oscillate the actuator to effect positive and opposite rocking of the transmitters.

5 8. In a harness-motion for looms, in combination, two oppositely - movable harness-frames, an oscillating actuator, means to oscillate it, and transmitting means between said actuator and each harness - frame, including a rocking member operatively and positively coöperating with the actuator, and a fixed fulcrum on which said rocking members are mounted side by side.

9. In a harness-motion for looms, in combination, two oppositely-movable harness-frames, a rocking transmitter positively connected with each harness-frame, each transmitter having a bifurcated extension provided with follower-rolls, a common actuator having cams to coöperate with the fol-

lower-rolls of the two transmitters, to rock the latter oppositely, and means to oscillate the actuator.

10. In a harness-motion for looms, in combination, two oppositely-movable harness-frames, two pairs of connected bent levers, positive connections between each pair and one of the harness-frames, an actuator positively coöperating with one of the levers of each pair, and means to oscillate said actuator and thereby rock oppositely the two pairs of connected levers.

In testimony whereof I have signed my name to this specification in the presence of two subscribing witnesses.

CHARLES F. ROPER.
